UNITED STATES PATENT OFFICE.

FRANK L. GOODRICH, OF CHICAGO, ILLINOIS.

COMBINED PRESSER-FOOT AND CLAMP FOR HOLDING SEWING-MACHINE ATTACHMENTS.

SPECIFICATION forming part of Letters Patent No. 324,247, dated August 11, 1885.

Application filed December 24, 1883. (Model.)

To all whom it may concern:

Be it known that I, FRANK L. GOODRICH, residing at Chicago, in the county of Cook and State of Illinois, and a citizen of the United States, have invented a new and useful Improvement in a Combined Presser-Foot and Clamp for Holding Sewing-Machine Attachments, of which the following is a full description, reference being had to the accompanying drawings, in which—

Figure 1 is a top or plan view; Fig. 2, a side elevation; Fig. 3, a rear elevation; Fig. 4, a front elevation; Fig. 5, a top or plan view of a hemmer and its attaching-arm; Fig. 6, a section on line $x-x$ of Fig. 5; Fig. 7, a bottom view of a hemmer and its attaching-arm; Fig. 8, a side elevation showing a modification in applying the clamp; Fig. 9, a section through the clamp on line $y-y$ of Fig. 8.

The object of this invention is to construct a presser-foot for sewing-machines from a single piece of suitable metal, and thereby dispense with the large portion of the labor heretofore required in milling and finishing up presser-20 feet, and also to combine with such presser-foot a clamping device by which other attachments can be secured to the foot and held firmly in position; and its nature consists in forming a presser-foot from a single strip or 25 bar of metal bent into shape to form the shank or head and the foot proper, as hereinafter more specifically described, and in combining with such presser-foot a coacting piece and a set-screw by which an arm or support carrying 30 a hemmer or other attachment can be readily and quickly secured in place, as hereinafter more specifically described, and pointed out in the claims.

In the drawings, A represents the head or 35 portion which is attached to the presser-bar, which head is formed by cutting out two circular rings, a , in each of which is an opening, A', to receive the end of the presser-bar, which rings are joined by a neck, a' , leaving 40 a space, A'', between the rings, as shown in Figs. 2 and 3. The neck a' has a screw-threaded opening to receive the stem of a set-screw, f , by which the device is firmly clamped to the presser-bar, and when bent into shape the 45 rings a stand in parallel planes and at right angles to the neck a' , as shown in Figs. 2 and 3.

B is the presser-foot, connected with the

head A by a strip, B', which strip and the presser-foot B continue out from the lower ring, a , of the head, as shown in Fig. 2, the 55 piece forming the presser-foot being of the required width for the width of the foot. As shown in Figs. 1 to 4, inclusive, the piece forming the presser-foot is turned at its forward end and runs back on itself, and its inner end 60 is turned at right angles, as shown in Fig. 2, and this turned portion b forms a clamp for holding other attachments. The necessary pressure for holding purposes is provided by a set-screw, e , the stem of which passes through 65 the standard B', and enters a screw-threaded opening in the end or jaw b' of the clamp, as shown in Fig. 2.

C is a plate-hemmer of the usual construction, attached to the end of an arm or support, 70 so as to properly coact with the presser-foot when in position for use.

D is the arm or support, having its end D' standing at right angles to the main portion, as shown in Figs. 5 and 7, and this end D' is 75 bent so as to have two parts, d and d' , which stand at right angles, or nearly so, to each other; and this end D' is slipped into the clamping device of the presser-foot to have one portion, d , between the presser-foot and the part b of 80 the clamp, and its other portion, d' , between the standard B' and the end or jaw b' of the clamp below the set-screw e , as shown in Fig. 2, so that by drawing the clamp b down by turning the set-screw the parts d and d' will 85 be firmly clamped, holding the bar D and the attachment which it carries firmly in position.

The rings a , with the neck a' , form a head for attachment to the presser-bar through the set-screw f , and the presser-foot and its standard are formed from the same piece of metal, and the blank from which these parts are formed can be cut from the plate by means of a suitable die. It will also be seen that by turning the portion which forms the presser-foot proper back on itself, as shown and described, a bite or clamp is likewise formed from the same piece of metal from which the head and foot are formed.

In use the presser-foot is secured to the bar 100 by slipping the head A on the bar and securing it by the set-screw f , and when the presser-foot is to be used alone this is all that is required; but when some other attachment is to

- be used in connection with the foot such attachment has its arm or support D slipped into the clamp and locked firmly by the set-screw e, and such attachment can be readily removed when through with by simply loosening the set-screw and withdrawing the arm or support from the clamp, leaving the presser-foot in condition for use without any other change.
- 10 Instead of forming the clamp from a continuation of the presser-foot, such clamp might be made of an independent piece, as shown in Fig. 8, in which case the portion b is shortened, and the portion b' is provided with side flanges, b'', which clasp the standard B', as shown in Fig. 9, and form guides to keep the movable portion of the clamp in place. The end D' of the arm or support carrying the attachment is slipped into place in the clamp

and held by the set-screw e in the manner already described for the other form of construction.

What I claim as new, and desire to secure by Letters Patent, is—

1. A presser-foot made from a single piece of material, having its lower extremity bent back upon itself to form a clamp, substantially as described.

2. A presser-foot made from a single piece of material, bent as shown and described, in combination with a clamp or jaw, b b', and set-screw e, for securing other attachments in position, substantially as specified.

FRANK L. GOODRICH.
